(57) **CLAIM**

The ornamental design for a workspace caddy, as shown and described.

DESCRIPTION

FIG. 1 is a right, top, front perspective view of a workspace caddy embodying our new design;

FIG. 2 is a front elevational view thereof;

FIG. 3 is a right side elevational view thereof, the left side elevational view thereof being a mirror image of the right side shown;

FIG. 4 is a rear elevational view thereof;

FIG. 5 is a top plan view thereof; and,

FIG. 6 is bottom plan view thereof.

The broken lines in the figures representing surfaces in FIGS. 1, 2, 3, 5 and 6 are included for the purpose of illustrating features that form no part of the claimed design.
